ATTORNEYS.

UNITED STATES PATENT OFFICE.

MILTON H. SHOENBERG, OF SAN FRANCISCO, CALIFORNIA.

LIGHTER.

Application filed June 8, 1922. Serial No. 566,830.

To all whom it may concern:

Be it known that I, MILTON H. SHOENBERG, a citizen of the United States, and resident of the city and county of San Francisco, State of California, have invented new and useful Improvements in Lighters, of which the following is a specification.

My invention has for its object a portable device adapted to be energized by electricity for the purpose of lighting cigars, cigarettes or the like. The device consists of a casing and an insulated base within which are arranged a switch and a heating coil and terminal connections to which a cord to supply energizing current may be attached.

Other objects will appear from the drawings and specifications.

By referring to the drawings my invention will be made clear.

Fig. 1 is a front view of my lighter.

Fig. 2 is a cross section of Fig. 1 on the line II-II thereof.

Fig. 3 is a front view with the heating coil and insulated cover and guard ring removed to show the recess in the base or casing, and on which are shown by dotted lines the relative position of the heating coil and its terminals and the wire connections thereto.

Fig. 4 is a cross section of Fig. 1 on the line IV-IV thereof.

Fig. 5 is a perspective view of the switch blade.

Throughout the figures similar numerals refer to identical parts.

A base member formed of rubber, bakelite, plaster or other suitable material and preferably of insulation material is shown by the numeral 1, although a metallic casting with an insulated lining may be employed in lieu thereof, if preferred. At 2 is shown a cover plate of mica or other insulation and mounted thereon a helical resistance coil 3 of resistance wire and which latter is adapted to be heated by the flow of electric current across the terminals 4, 5. A guard ring 6 surrounds the exposed heated parts, having a suitable opening therein to admit of a cigar or cigarette being passed therethrough and against the helical wire 3, the heat of which when energized, lighting the cigar. The terminals 4, 5, extend

through the plate 2 and are provided with lock nuts 7, 8, which securely hold the helical coil to the insulated cover 2, leaving the said column terminals 4, 5, extending downward as at 9, 10, until they contact with and are supported from the bottom or floor 11 of the recess 13 in the casing 1. A hook or other suitable means by which the lighter may be suspended is indicated at 14 and fastening rivets or screws for the ring 6 are shown at 15, 16. The electric cord connections 17, 18, convey energizing current for the resistance coil 3; 17 being attached to the terminal 10 and 18 being soldered to the switch member 19. This latter is formed with a spring tension by which it normally occupies the full line position of Fig. 3 bearing against the push button 20 and normally in its extended position of Figs. 1, 2, 3. When the said push button is depressed into the position 21, the spring 19 is shifted into its dotted position in contact at such time with the column terminal 9 of the coil 3, thus completing a circuit from 18 through 19, 9, 3, 10, back to connection 17 and energizing the helical coil 3 which now becomes sufficiently heated to light the cigar, cigarette or other article which it is desired to fire. The inner periphery of the recess 13 forms a bearing surface on which the projecting portion 22 of the spring 19 bears when the spring is actuated from the full line to the dotted position of Fig. 3. The recess at 23 is for retaining the cover 2 and the ring 6 flush with the surface of the casing 1 when the parts are assembled at which time the terminals 9, 10, bearing upon the surface 11 firmly support the central portions of the cover 2 and helical coil 3 so that the parts will not be distorted when the cigar is pressed against the incandescent coil. The helical coil is made with a straight line axis and of relatively coarse resistance wire so that it is not normally subject to easy breakage or disruption and when utilizing six or twelve volts corresponding with the storage battery or current generated in most automobiles, very quickly comes to the incandescent point with an expenditure of approximately $1\frac{1}{2}$ amperes and it is therefore well suited without undue strain upon the battery for service in an au-

tomobile. The proportions of the helix to give the desired results are preferably made substantially as shown where its length is substantially eight times its diameter, thus giving great efficiency and stability in service.

It will be seen that the cover plate 2, columns 9, 10, and helix 3 form a unitary structure easily replaceable under the ring 6 and in casing 1, should the helix at any time become damaged.

I claim:

1. In an electric lighter a base member of annular form, a bottomed annular recess therein, an insulating plate covering said recess, a resistance wire mounted on said plate, switch means mounted in said recess and adapted to control the energization of said resistance coil, said resistance wire wound in helix form whose length is not less than six times its diameter and whose ends are fixed to column supports, and column supports fixed in said plate and adapted to contact with the bottom of said recess to support the plate against distortion, and a guard ring closing the joint between the base member and the plate.

2. An electric lighter as set forth in claim 1 wherein the switch means includes a push button extending through the side of the annular base and a spring therein adapted to contact with a connection to the resistance wire.

3. An electric lighter as set forth in claim 1 wherein the switch means includes a push button extending through the side of the annular base and a spring therein adapted to contact with a connection to the resistance wire, the other end of said spring fixed in a groove in said recess and a spacer between the spring and the inner wall of the recess substantially intermediate the spring ends.

4. In an electric lighter a base member of annular form, a bottomed annular recess therein, an insulating plate covering said recess, a resistance wire mounted on said plate, switch means mounted in said recess and adapted to control the energization of said resistance coil, said resistance wire wound in helix form whose length is not less than six times its diameter and whose ends are fixed to column supports.

5. In an electric lighter a base member of annular form, a bottomed annular recess therein, an insulating plate covering said recess, a resistance wire mounted on said plate, switch means mounted in said recess and adapted to control the energization of said resistance coil, said resistance wire wound in helix form whose length is not less than six times its diameter and whose ends are fixed to column supports, and column supports fixed in said plate and adapted to contact with the bottom of said recess to support the plate against distortion.

6. In an electric lighter a base member

of annular form, a bottomed annular recess therein, an insulating plate covering said recess, a resistance wire mounted on said plate, switch means mounted in said recess and adapted to control the energization of said resistance coil, said resistance wire wound in helix form whose length is not less than six times its diameter and whose ends are fixed to column supports, and column supports fixed in said plate and adapted to contact with the bottom of said recess to support the plate against distortion, and a guard ring closing the joint between the base member and the plate.

7. An electric lighter as set forth in claim 4 wherein the switch means includes a push button extending through the side of the annular base and a spring therein adapted to contact with a connection to the resistance wire.

8. An electric lighter as set forth in claim 5 wherein the switch means includes a push button extending through the side of the annular base and a spring therein adapted to contact with a connection to the resistance wire.

9. An electric lighter as set forth in claim 6 wherein the switch means includes a push button extending through the side of the annular base and a spring therein adapted to contact with a connection to the resistance wire.

10. An electric lighter as set forth in claim 4 wherein the switch means includes a push button extending through the side of the annular base and a spring therein adapted to contact with a connection to the resistance wire, the other end of said spring fixed in a groove in said recess and a spacer between the spring and the inner wall of the recess substantially intermediate the spring ends.

11. An electric lighter as set forth in claim 5 wherein the switch means includes a push button extending through the side of the annular base and a spring therein adapted to contact with a connection to the resistance wire, the other end of said spring fixed in a groove in said recess and a spacer between the spring and the inner wall of the recess substantially intermediate the spring ends.

12. An electric lighter as set forth in claim 6 wherein the switch means includes a push button extending through the side of the annular base and a spring therein adapted to contact with a connection to the resistance wire, the other end of said spring fixed in a groove in said recess and a spacer between the spring and the inner wall of the recess substantially intermediate the spring ends.

13. In an electric lighter of the character described, a base member of annular form, a bottomed annular recess therein, an insu-

lating plate covering said recess, a resistance wire mounted over said plate, switch means mounted in said recess and adapted to control the energization of said resistance coil, and switch means comprising a push button extending thru the side of the annular base and a spring therein adapted to contact with a connection to the resistance wire, the other end of said spring fixed in a groove in said recess and a spacer between the spring and 10 the inner wall of the recess substantially intermediate the spring ends.

MILTON H. SHOENBERG.
